UNITED STATES PATENT OFFICE.

HENRY JANSSEN, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

BRAIDING-MACHINE.

1,325,946.

Specification of Letters Patent. Patented Dec. 23, 1919.

Application filed October 3, 1919. Serial No. 328,176.

To all whom it may concern:

Be it known that I, HENRY JANSSEN, a citizen of the United States, residing at Wyomissing, in the county of Berks and 5 State of Pennsylvania, have invented certain new and useful Improvements in Braiding-Machines, of which the following is a specification.

My invention relates particularly to what 10 are termed lace-braiding machines, in which the carrier-drive mechanism provides for engaging or disengaging the carrier-drive member of different race-circles as determined by a jacquard or pattern controlling 15 mechanism.

Each of such carrier-drive members commonly has a clutch engagement with the corresponding drive gear, and a vertically guided clutch-operating bar therefor to 20 which periodic movement is imparted as required to give desired intermittent movement to the engaged carriers.

The main object of my invention is to provide convenient and economical actuating connections between the circularly arranged series of clutch-operating bars and the pattern mechanism; and to this end it consists in providing each of the former with a self-carried clutch lever pivoted to 25 one side of the bar and having an oppositely extending fulcruming arm normally held in contact with the machine frame by the clutch-releasing spring; such lever being capable of ready rotary adjustment upon 30 the rod so as to bring its pivotal swing into the plane of its operating connection to the pattern mechanism; and no connection of the lever to the machine frame being required. The invention is fully described in 35 connection with the accompanying drawing and is specifically pointed out in the claims.

Figure 1 is a vertical section of a single clutch-operated carrier drive mechanism.

Fig. 2 is a cross-sectional view on the line 45 2-2 of Fig. 1, showing the adjustably connected lever-pivoting arm.

Figs. 3 and 4 are opposite edge-wise views of the lever connection.

Fig. 5 is a diagrammatic view indicating 50 a plurality of race-circle posts with adjacent clutch operating rods and pattern control connection to the latter.

Fig. 1 shows a single race-circle post 10 having mounted thereon a constantly rotated drive gear 11 and a carrier-drive mem-

ber 12 movable into or out of clutch engagement with said drive gear 11; with a clutch-bar 13 vertically guided in the machine frame and having the end portion thereof which depends below the bottom plate 14 of 60 the machine provided with an operating connection 15 to a pattern control mechanism; a spring 16' being arranged to normally raise the carrier-drive member 12 out of operative engagement with its drive 65 gear 11. This general construction is known, and the stop washer 30 which serves to hold the disengaged member is shown in Rahm Patent No. 1,282,945 of October 29, 1918. The connections 15 to the several 70 clutch bars 13 of different race-circles, extend in different lines to the pattern mechanism as indicated in Fig. 5.

In my improved construction each of these connections 15 is secured to a clutch 75 lever 16 which is carried by its clutch bar 13 independently of the machine frame. A pivot arm 17 of said lever is connected to the laterally extending arm 18 of a separately formed bar attachment 19, the hub 80 of which latter is rigidly secured to the depending end of the bar by means of a setscrew 20; and a fulcruming arm 21 of said lever extends to the diametrically opposite side of the rod and has an end portion 22 85 arranged to bear against the bottom plate 14 of the machine. So that when thus connected to the clutch bar 13 said fulcruming end 22 of the lever will be normally pressed against said bottom plate 14 by the action of 90 the spring 16, and when such pressure is increased by a pull upon the depending arm 23 of the lever exerted through its pattern connection 15, it will serve to pull down the clutch bar (as indicated by the dotted lines) 95 and so engage the clutch members 11 and 12. The slight swing of the lever required to effect such engagement, and the length of the slender connection 15, permit of the latter being loosely and adjustably connected 100 to the lever arm 23 without jointing, as shown.

It will be seen that my invention greatly simplifies the construction and assembling of the machine; the combined lever 16 and 105 bar attachment 19 being secured to the depending portion of each previously mounted clutch-bar 13 in readily adjusted alignment with the particular direction of its pattern connection 15, and being very conveniently 110

and satisfactorily operative without providing any frame connection for the lever.

What I claim is:

1. In a braiding machine comprising a bottom plate provided with a series of race-circle posts each having mounted thereon a driving gear and a clutch-engaged carrier-drive member; a series of clutch-operating bars vertically guided in said bottom plate, each of said bars being provided with a spring adapted to normally raise the same, a lateral extension at its depending end, and a lowering lever therefor pivoted to said lateral bar extension and having a fulcrumming arm pressed against said bottom plate at the opposite side of said rod.

2. In a braiding machine comprising a bottom plate provided with a series of race-circle posts each having mounted thereon a driving gear and a clutch-engaged carrier-drive member; a series of clutch-operating bars vertically guided in said bottom plate, each of said bars being provided with a spring adapted to normally raise the same, a laterally extending pivot arm adjustably secured to its depending end, and a lowering lever pivoted to said arm and having a fulcrumming arm pressed against said bottom plate at the opposite side of said bar.

In testimony whereof I affix my signature.

HENRY JANSSEN.
